SHOWER STALL DOOR HINGE

William Stahl, Los Angeles, Calif.

Application December 7, 1936, Serial No. 114,571

7 Claims. (Cl. 189—46)

My invention relates to hinges for doors, and particularly, although not necessarily to hinges for the doors of shower stalls.

Such stall door hinges as heretofore proposed are of the butt type and, hence, structurally complex and therefore costly to manufacture, and ineffective to prevent water leaking outwardly between the hinged edge of the door and the doorway.

It is a purpose of my invention to provide a hinge for shower stall doors characterized by its structural simplicity, durability, low cost of manufacture and easy mode of assembly, and wherein the parts of the hinge are so related one to the other that in applied position on a door and jamb and the door in closed position, the hinge functions to prevent leakage of water from the stall outwardly between the door and jamb.

I will describe only one form of hinge for shower stall doors, embodying my invention, and will then point out the novel features thereof in claims.

In the accompanying drawing:

Fig. 1 is a view showing in front outside elevation a door applied to a shower stall and in closed position, and having applied to the door and stall one form of hinge embodying my invention.

Fig. 2 is a fragmentary view similar to Fig. 1 viewing the door from the inside and with the latter in open position.

Fig. 3 is an enlarged transverse sectional view taken on the line 3—3 of Fig. 1.

Fig. 4 is a view similar to Fig. 3 showing the door in open position, and taken on the line 4—4 of Fig. 2.

Fig. 5 is an enlarged sectional perspective view of the hinge only.

Referring specifically to the drawing, my invention in its present embodiment consists of a hinge made of two main parts, one part comprising a jamb strip 15 constructed of metal, and the other part comprising a metal plate or a metal frame 16 of a door, and particularly a door for closing the doorway of a shower stall where, as shown in Figs. 1 and 2, the frame supports a plate of glass 17 therein.

The jamb strip 15 is adapted to be secured to one vertical tiled wall 18 of the doorway of the shower stall. This strip 15 is coextensive in length with the wall 18, and screws 19 are employed for fixedly securing the strip to the wall. At the inner edge or stall side edge of the jamb strip it is formed with an abutment flange 20 extending at right angles therefrom. It is against this flange 20 that the door frame 16 is

adapted to abut when the door is in closed position, as shown in Fig. 3, and in this position of the door the adjacent vertical wall 18a of the door frame is parallel to the jamb strip.

At its outside edge the jamb strip 15 is formed with an elongated tongue 21 coextensive in length with the strip and curved inwardly to form a coextensive groove 22 at the inner side thereof. Adjacent and to the inner side of the tongue 21 the strip itself is formed with a groove 23 coextensive in length therewith. The transverse curvature of this groove is such that it coacts with the transverse curvature of the groove 22 to form therewith a groove of involute curvature in cross section.

The plate or frame part 16 of the hinge is formed with a tongue 24 complementary to and coextensive in length with the tongue 21. This tongue 24 is likewise transversely curved but oppositely to that of the tongue 21 to define a groove 25 the transverse curvature of which is struck from a single radius. Thus, the adjacent wall 18a of the door frame 16 from which the tongue projects, is tangent to this groove curvature.

With a hinge constructed as described, it is necessary in order to operatively connect one hinge part to the other to present the end of one tongue to that of the other, so that the tongue 24 can be extended endwise into the involute groove of the other tongue 21 and the latter tongue extended into the groove 25 of the tongue 24. In this manner the two tongues are interconnected to allow free turning movement of one on the other through a 90 degree angle. Because of the transverse curvatures of the grooves 22, 23 and 24 and the outside curvatures of the tongues, the tongues can be turned one on the other without any lateral or transverse movement of the tongues relatively. In this manner any possibility of the door sagging on the jamb is prevented.

For securing the tongues against endwise relative moment, when once assembled as described, screws 26, 26 are threaded in the strip 15 (Fig. 3) so as to extend into slots 27 formed transversely in the tongue 24 (Fig. 5). Such a securing means permits the necessary turning movement of one tongue on the other, yet the tongues cannot shift lengthwise relatively.

Manifestly, where my hinge is applied to a shower stall door, it is necessary to first apply the jamb strip to the door frame before the former is secured to the wall 18. Once the jamb strip is secured in position with the abutment flange 20 innermost, the two hinge tongues serve

to support the door for swinging movement from the closed position shown in Figs. 1 and 3 to the right angular open position shown in Figs. 2 and 4. The open position of the door is defined by the 5 wall 16* abutting the flat portion of the tongue 21, while the closed position is defined by the door frame abutting the jamb strip.

In the adaptation of my hinge to a shower stall door, it provides the advantage of preventing 10 water leaking between the parts of the hinge when the door is in closed position. From an inspection of Fig. 3, it will be apparent that the free longitudinal edge of one tongue contacts throughout its length with the grooved side of the other 15 tongue when the door is in closed position. In this manner a double seal is formed between the two tongues which prevents the passage of water outwardly from between the tongues even when the water is sprayed directly against the hinge. 20 Although I have herein shown and described only one form of shower stall hinge embodying my invention, it is to be understood that various changes and modifications may be made herein without departing from the spirit of my invention 25 and the spirit and scope of the appended claims.

I claim:

1. In combination; a vertical jamb strip having a flange on one vertical edge the other vertical edge being formed with a groove, and a 30 tongue both of which are coextensive in length with the jamb strip and curved transversely inward, with the curve of the groove and the inner curve of the tongue combining to form an involute curve while the curvature of the tongue's outer 35 sides is struck from a single radius and tangent to the adjacent vertical edge of said strip; a tongue on one vertical edge of the door coextensive in length therewith disposed between the sides thereof, and curved transversely outward 40 from a single radius to form on its concave side a groove tangent to the vertical door edge, said tongues extending into the grooves of each other so that the door is mounted on the jamb to swing from a closed position in which the door abuts 45 the flange, and the free vertical edges of the tongues contact with the walls of the respective tongue grooves for forming a liquid tight joint between the tongues, to an open position in which the confronting walls of the tongues contact with each other and the confronting walls of the door 50 and the jamb strip abut each other; and means for securing the tongues against endwise relative movement.

2. In combination; a vertical jamb strip hav-

ing a flange on one vertical edge thereof and an integral tongue on the other vertical edge coextensive in length therewith and continuously curved inwardly from said edge; a door having a frame; a tongue on one vertical edge of the frame 5 coextensive in length therewith, situated between the sides thereof, and curved transversely outwardly, said tongues engaging one within the other so that the door frame is mounted on the jamb to swing from a closed position in which the 10 door frame abuts the flange and the free vertical edges of the tongues contact with the respective confronting walls of the tongues, to an open positioning in which the confronting walls of the door frame and the jamb strip contact with each 15 other.

3. A hinge comprising a strip having a tongue thereon curving inwardly away from an outer longitudinal edge thereof to define a groove in said strip, a second strip having a tongue thereon curving outwardly toward an outer longitudinal edge thereof to define a groove in said second strip, said tongues having interlocking engagement with one another whereby each of their edges are in simultaneous contact with the wall of 25 the groove formed by the other tongue when said longitudinal edges face in the same general direction.

4. A hinge as defined in claim 3, wherein the edges of said tongues face in generally opposite 30 directions when simultaneously contacting the walls of said grooves.

5. A hinge as defined in claim 3, wherein the wall of one of said grooves is an arc of a circle, and the edge of the tongue engageable therewith 35 contacts it continuously to prevent relative translatory lateral movement between said strips.

6. In combination, a stationary jamb strip having a tongue thereon curving inwardly away from an outer longitudinal edge thereof to define an 40 inwardly opening groove in said strip, a door adapted to open outwardly and having a tongue thereon curving outwardly toward a longitudinal edge thereof to define an outwardly opening groove in said door, said tongues having interlocking engagement, with at least an edge of one tongue in contact with the wall of the groove 45 formed by the other tongue.

7. The combination defined by claim 6, wherein the edges of said tongues are in simultaneous 50 contact with the wall of the groove formed by the other tongue when said door is in closed position.

WILLIAM STAHL.
